UNITED STATES PATENT OFFICE

FREDERIC K. HEYER, OF STAMFORD, CONNECTICUT, ASSIGNOR TO THE YALE & TOWNE MANUFACTURING COMPANY, OF STAMFORD, CONNECTICUT

CYLINDER LOCK

Application filed October 13, 1926. Serial No. 141,302.

This invention relates to improvements in cylinder locks and more particularly to the plug structure.

In accordance with the present method of making plugs for cylinder locks, the plug has usually been made in one complete die cast unit. It has been found that on account of the necessary machining, the sectional area is so reduced that the plug is structurally weak and unequal of itself to withstand the strain of the operation of the bolt under certain conditions.

An object of my present invention is to reinforce the core of the plug structure so that it will effectually withstand any strain to which it may be subjected, when in use, and so that the plug case shall be reinforced in such manner that in the event that it becomes broken by violence or attack, the structure will still be held in operative position for the key.

A further object is to provide the core of a plug structure, with a reinforcing jacket which shall be so connected therewith that it will always turn with said core and so that the said jacket will carry all the strain incident to operation of the lock, thus retaining the economical method of forming the tumbler, spring and key openings in the plug by means of die casting or otherwise and also obtaining the required strength and rigidity necessary for the proper operation of the lock.

With this and other objects in view, the invention consists in certain novel structure as hereinafter set forth and pointed out in the claims.

In the accompanying drawings;

Figure 1 is an enlarged longitudinal sectional view showing an embodiment of my invention;

Figure 2 is a rear end view;

Figure 3 is an end view (on a smaller scale) of the lock cylinder;

Figure 4 is an end view of the plug jacket member;

Figure 5 is an end view of the plug core, and

Figures 6 and 7 are face views showing

respective sides of the locking plate which carries a roll-back pin.

In the drawings, the cylinder of the lock is shown at 1 and provided with grooves 2 which receive tumblers carried by the plug structure of the lock as will be readily understood.

The plug structure comprises a core member 3 (preferably of the die-cast type) having a key-way 4 and suitable slots 5 to receive spring-pressed tumblers (not shown), and a reinforcing jacket 6, preferably of wrought metal and having tumbler slots or openings 7. The reinforcing jacket 6 closely surrounds the core member 3 and at one end is provided with a flanged head 8 which may be made as an integral part of the jacket and is provided with a key slot 9. A portion of a key is shown at 10.

At its rear end, the jacket 6 is provided with a plurality of lugs 11 which project through openings 12 in a locking plate 13 and are upset against the rear face of said plate as shown in Figure 1. The plate 13 is made with a central angular opening 14 which receives a similarly shaped enlargement or projection 14^a on the rear end of the plug core. It will be apparent that the connection of the jacket with the plate 13 and the connection of the plug core with said plate, the jacket will be so secured to the core that these parts will always turn together and the jacket will sustain all strains to which the plug structure may be subjected during operation of the lock, thereby most effectually relieving the die-cast core of such strains and protecting the same from breakage or injury to which the core might be subjected if not reinforced.

The plate 13 constitutes a locking member between the reinforcing jacket and the core of the plug structure, and it also provides a carrier for a roll-back pin 15. This pin is made with a shank which passes through the plate and is upset, the enlargements 16 thus formed on the inner face of the plate entering aligning notches 17, 18 in the plug core 3 and jacket 6 respectively, thus assisting in preventing relative turning movement of said core and jacket.

The cylinder 1 is provided at its rear end with a recess 19 forming stop shoulders 20 and the plate 13 is provided with lugs 21 which enter the recess 19 and are cooperable with the stop shoulders 20 to limit the turning movement of the plug structure of the lock.

Having fully described my invention what I claim as new and desire to secure by Letters Patent, is:—

10. 1. A plug structure for a cylinder lock, comprising a core member, a reinforcing member surrounding the same, said reinforcing member being independent of said core member and a cam plate secured to said reinforcing member and having connection with the core member, whereby said members are rotatable together.

20. 2. A plug structure for a cylinder lock, comprising a core member, a reinforcing jacket therefor, said jacket having lugs at one end, and a plate having connection with the core member and provided with openings receiving the lugs on the jacket.

25. 3. A plug structure for a cylinder lock, comprising a core having a projection at one end, reinforcing jacket for said core member, said jacket having projections at one end, and a plate having openings receiving the projections on the jacket, said lugs being upset, and said plate having an opening receiving the projection on the core member.

35. 4. A plug structure for a cylinder lock, comprising a core member, a reinforcing jacket for the same, said jacket having an integral flanged head at one end and projections at the other end, and a plate having openings receiving the projections on the jacket, and means connecting said plate with the core member.

40. 5. In a cylinder lock, the combination with a lock cylinder, of a plug core, a reinforcing jacket for said core, said core and jacket having aligning recesses, a plate secured to said jacket and connected with the core member, a pin secured to said plate and having an upset portion at its inner end entering said aligning recesses in the core member and jacket.

50. 6. In a cylinder lock, the combination with a lock cylinder having stop shoulders at one end, of a plug core, a reinforcing jacket therefor, a plate secured to said jacket and having connection with said core, stop means on said plate cooperable with the stop shoulders on the cylinder, and a roll-back pin carried by said plate and having a part interlocking with the core and jacket.

60. 7. A plug structure for a cylinder lock, comprising a core member and a reinforcing jacket therefor, said reinforcing jacket being independent of said core member, a cam member, a means for independently securing said jacket and said core member to said cam member.

70. 8. A plug structure for a cylinder lock, comprising a core member of the sliding tumbler type, a reinforcing jacket for the core member extending from end to end of said member and rotatable therewith, said jacket being independent of said core member, a cam member, and means for independently securing said jacket and said core member to said cam member.

75. 9. A plug structure for a cylinder lock, comprising a cast core member, a wrought reinforcing jacket therefor and rotatable therewith, said jacket being independent of said core member, a cam member, means for securing the core member to said cam member, and other means for independently securing said jacket to said cam member.

80. 10. A plug structure for a cylinder lock, comprising a core member and a reinforcing jacket, said jacket being independent of said core member, a cam member, and means for independently securing said jacket and said core member to the cam member, whereby said parts may move as a unit.

85. 11. A plug structure for a cylinder lock, comprising a cast core member and a wrought metal reinforcing jacket surrounding the same, said jacket being independent of said core member, a cam member, means for securing the core member to the cam member, and independent means for securing said jacket member to said cam member.

90. 12. A plug structure for a cylinder lock, including a die cast core member, an independent reinforcing jacket therefor and movable therewith, a cam member, and means rigidly securing said jacket to said cam member.

95. In testimony whereof, I have signed this specification.

FREDERIC K. HEYER.
